(57) **CLAIM**

We claim the ornated design for a stand for a barbecue, as shown and described.

DESCRIPTION

FIG. 1 is a perspective view of the stand for a barbecue showing our new design in an extended, use configuration;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front perspective view of the stand for a barbecue in a collapsed, storage configuration; and,

FIG. 10 is a rear perspective view of the stand for a barbecue in the collapsed, storage configuration.
